CLAIM

The ornamental design for a nail polisher for animals, as shown and described.

DESCRIPTION

FIG. 1 is a front elevational view of a nail polisher for animals showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a bottom, front and left side perspective view thereof;

FIG. 8 is a bottom, front and left side perspective view showing the nail polisher for animals in an open state; and, FIG. 9 is an enlarged view of portion 9 in FIG. 7.

The broken lines in the drawings illustrate portions of the nail polisher for animals which form no part of the claimed design.

1 Claim, 8 Drawing Sheets
